TELEPHONE PAY STATION

Abraham Weiss and Joseph Weiss, New York,
N. Y.

Application November 5, 1936, Serial No. 109,232

4 Claims. (Cl. 194—98)

This invention relates to telephone pay stations and particularly to coin receiving boxes in which the bridging of the electric switch or make and break mechanism for the electric connections is effected by the deposit of the coin or token.

Our invention has for its principal object to provide means whereby the deposit of slugs or the like in lieu of genuine coins in the coin boxes can be easily and quickly detected.

10 Another object of this invention is to provide a construction whereby the token deposited in said coin box will be made visible outside the telephone booth so that the person depositing a slug or non-genuine coin can be apprehended before he leaves the telephone booth.

With these and other objects in view our invention consists in the novel construction, combination and arrangement of parts as will be more fully described and defined in the appended 20 claims.

In the accompanying drawing which constitutes part of this specification and in which similar reference characters denote corresponding parts

25 Fig. 1 is a reduced perspective view of a booth containing the coin box and the means for rendering visible the deposits outside said booth;

Fig. 2 is a vertical sectional elevation of the coin box embodying our invention; and

30 Fig. 3 is an enlarged vertical section of a detail of the coin box and of the means for reflecting the deposited token outside the telephone booth.

In the drawing 10 denotes the telephone booth with the coin box 11 fixed inside said booth, as 35 usual, to one of the side walls 10^a thereof.

The coin box 11 is provided on its top with the usual slots or openings 11^a through which coins of different denominations, such as nickels, dimes and quarters, are deposited. Extending 40 downwardly from said slots or openings are chutes 12 of well known construction, all terminating at their lower ends into a hopper 13 into which the deposited tokens are adapted to drop and from which they are to be delivered into a 45 receptacle or trap 14 mounted below said hopper. This receptacle is composed of two sections 14^a, 14^b pivoted at their upper edges, as at 14', and is open on top, as at 15', said opening coinciding with the opening 13' in the bottom of the hopper 13, so that the tokens dropping into the hopper will pass through the openings 13' and 15' into the space 15 between the wings or side walls of the two sections 14^a, 14^b of the receptacle 14. In width this space 15 is slightly larger than the 55 thickness of an ordinary coin, as for instance

that of a nickel, and in height and length it may be so admeasured as to accommodate a number of coins to rest on top and alongside one another. The bottom of said space 15 is also open, as at 15^a, and extending longitudinally 5 below the said opening 15^a is a cylindrically shaped metal rod 16 which is suitably pivoted at one end, as at 16', and whose opposite end 16^a carries an electric contact piece 17 which is adapted to cooperate with a contact 18, said 10 contact pieces 17 and 18 constituting a part of the make and break mechanism of an electric circuit x for the telephone connections. Normally, that is in the absence of a coin or token in the space 15, the rod 16 will under the action 15 of a spring 19 be held so as to break the communication between the contacts 17 and 18. The side walls or wings of the sections 14^a, 14^b of said receptacle have extensions 14³, 14⁴ below the rod 16 which normally are adapted to bear 20 against one another to form a closure which will prevent the tokens from dropping out from the space 15.

Each wing or side of said receptacle is connected by a rod 20 to the armature 21 of a solenoid 22 adapted to be energized by the electric circuit y controlled by the operator in well known manner. When the proper amount has been deposited, and the user gets the telephone connection desired, the operator will close the circuit 30 through the right solenoid, as a result of which the right wing or section 14^a will be swung laterally to permit the coins to drop down a chute or slide 23 leading into the coin collecting box 24. If, on the other hand, the user fails to get the 35 desired connection or for other reasons the money is to be returned to the user, the operator will cause the left side solenoid to be energized thereby causing the left wing or section 14^b of the receptacle to swing open to thus permit the 40 tokens to drop over the chute 23' into the coin return compartment 25.

The wings or sections 14^a, 14^b of the receptacle 14 may be provided with counter weights 26 or actuated by springs so that when one or the other 45 of the wings is swung away from its mate, the latter may swing somewhat in the same direction as indicated by dotted lines to project beyond the crest 23^a of the two chutes and thereby prevent the coins from falling into the wrong compartment. 50

The side walls of these sections are made of glass or other transparent material or provided with such windows so that all tokens deposited in the space 15 of said receptacle are visible through 55

said sides. Arranged in the vicinity of said receptacle is an electric light *L* adapted to illuminate the tokens in said receptacle. This light may be ignited through the electric circuit *x* which is controlled from the make and break mechanism 5 17 and 18 operated by the rod 16 when a token is deposited into said receptacle and rests on said rod.

Suitably arranged and leading outwardly from 10 the telephone cabinet 11 and through the booth 10 to any convenient place is a periscopic tube 27 of well known construction. The inner end or mouth portion 27' of said periscope is adapted to face one of the transparent wings or sides of 15 the receptacle and is provided with a suitable lens 28 through which the tokens *t* will be thrown onto a reflecting prism or mirror 29 and thence through similar prisms 30 located at the other end of the periscope.

20 In the example shown, the outer end 27' of the periscope is shown at the rear and at the top of the booth. This end may be extended forwardly and provided with a magnifying lens 31 arranged in a somewhat slanting position so that anybody 25 standing outside of the booth may see the tokens reflected therein through the periscope.

Instead of terminating on top of the booth, the periscope may be extended to any part of the particular premises where the booths are located, as 30 for instance, if located in a drugstore, the outer end of the periscope may terminate in the rear of the store where a clerk may be able to always observe whether the coins deposited by the occupant of the booth are genuine.

35 It is, of course, obvious that various modifications may be made in the construction and arrangement of the parts without departing from the principle of our invention.

We, therefore, do not wish to limit ourselves to 40 the details shown and described.

What we claim is:

1. In a telephone pay station, the combination with a coin box or cabinet having coin delivery means, of a transparent coin trap concealed within said cabinet adapted to trap the coins in upstanding position, a coin display means remote from said cabinet and means leading from a point opposite said trap to said coin display means for rendering the individual coins contained in said trap visible through said coin display means. 5

2. In a telephone pay station, the combination 10 with a booth and coin box or cabinet therein having coin delivery means, of a transparent coin trap concealed in said cabinet and holding the coins in upstanding position, a coin display means on said booth, and means disposed opposite said 15 transparent coin trap within said cabinet and leading outwardly to said coin display means for rendering the individual trapped coins visible through said coin display means.

3. In a telephone pay station, the combination 20 with a box or cabinet having coin delivery means, of a transparent coin trap concealed within said cabinet and holding the coins in upstanding position, a coin display means remote from said cabinet, means for illuminating the coins in said 25 trap, and means disposed opposite said transparent trap within said cabinet and leading outwardly to said coin display means for rendering the individual trapped coins visible through said coin display means. 30

4. In a telephone pay station, the combination 35 with a coin box or cabinet having coin delivery means, of a transparent coin trap within said cabinet, a coin display means remote from said cabinet, and means for rendering the coins in said trap visible through said coin display means, said means including a tube leading from a point opposite said transparent trap outwardly from said cabinet to said display means.
